UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

STEAM-HEATING APPARATUS.

1,295,302.

Specification of Letters Patent. Patented Feb. 25, 1919.

Application filed October 10, 1917. Serial No. 195,676.

To all whom it may concern:

Be it known that I, EDWARD E. GOLD, a citizen of the United States of America, residing in the borough of Manhattan, city, county, and State of New York, have invented certain new and useful Improvements in Steam-Heating Apparatus, of which the following is a specification.

This invention relates to steam heating systems of the general character set forth in my Patent No. 1,168,720, dated January 18, 1916. An object of the present invention is to substitute for the bow thermostat shown in that patent, a diaphragm thermostat or thermostatic vessel consisting of a disk-shaped device of thin metal containing a highly volatile liquid. Such diaphragm thermostats are much more sensitive and possess many advantages which are well recognized in the art.

In the drawings,—

Figure 1 is a vertical mid-section of the improved structure, taken on the line 1—1 of Fig. 2;

Fig. 2 is a vertical transverse section on the line 2—2 in Fig. 1;

Fig. 3 is a perspective view of a detail;

Fig. 4 shows a fragment of Fig. 1, illustrating a stop cap.

The shell or casing A, with its cover B, the steam-inlet connection C, steam valve D, injector nozzle E, outlet F to the radiator, return connection G from the radiator, and drip connection H, are all of the known construction and substantially similar to that set forth in my said patent. The valve D is mounted on a primary stem I pressed back by a spring J in a known manner.

Against this stem abuts the end of a secondary stem or stem section K which receives (indirectly) the thrust of the thermostat. The subdivision of the valve stem into members I and K is convenient but not essential.

The thermostat M is the usual construction of diaphragm thermostat, being mounted on a fixed abutment N, which is conveniently attached to the cover B. This attachment also provides a pivotal bearing a for a lever P which receives at or near its middle the thrust of the thermostat, and at its free end communicates this thrust to the stem K to close the valve D.

Inasmuch as the diaphragm has a substantially invariable range of expansion and contraction between the extremes of heat

and cold to which it is subjected, and as the valve D has a fixed play to and from its seat, it is necessary to provide for bringing these respective movements into working relation in order that the apparatus may operate correctly. To do this in the practical installing of the parts, some means must be provided for adjusting the point of engagement of the lever P with the valve stem. In the construction shown this is accomplished by making the secondary stem K in two parts, K and K', which are relatively adjustable, the part K' carrying a collar b which receives the thrust of the lever, and the other part K conveying this thrust to the valve stem I. A convenient construction is that shown, in which the stem K is reduced at c to smaller diameter, and the stem K' is formed as a tube d which has the collar b fixed on it at one end, and at the other end 75 is counterbored and internally threaded to receive an adjusting screw e, the inner end of which abuts against the reduced stem c. By screwing the screw in or out the relation of the two stems may be varied, in order to insure that the normal expansion of the thermostat, when heated by the exhaust steam or vapor from the radiator, shall close the valve D. To prevent turning the stem d when the screw e is turned, the collar b is 85 formed with a flat portion b' (Fig. 1) which is engaged in the forked end of the lever P. To prevent tampering with the screw e, and also to make the point of emergence of the stem d steam-tight, an outer cap f is screwed on, engaging preferably with a threaded sleeve or nipple g.

Valve devices of this character are constructed to utilize the steam injector E to cause an upward suction through a branch F' communicating with the chamber within the casing A in order, when the device is applied at the top of a high radiator (as shown in Fig. 1 of my said patent), to draw exhaust steam from the lower end of the radiator upward, so that the heat of this steam may operate the thermostat M. An attendant disadvantage of this, however, is that the hot condensation falls down through the passage F' and would drop onto the thermostat if means were not provided to divert it. According to my present construction, this diversion is effected by means of a shield Q of sheet-metal, which is placed in the position shown best in Fig. 2, being 110

upheld by its ends resting on the sleeves *g h* (Fig. 1), and being held against displacement by ears *i i* (Fig. 3). This shield does not close the opening *F'*, but diverts any falling condensation and directs it down at the sides, where it is not likely to influence the thermostat.

When the thermostatic valve is set at a level about as low as the bottom of the radiator, the injector *E* is unnecessary and it is then desirable to close off the opening *F'*, for which purpose I provide a screw-cap *R* which screws on the threaded end of the connections through which the passage *F'* is formed, in the manner shown in Fig. 4. This enables the same structure to be used in either location by making this trifling change, *i. e.*, adding *R* and discarding the shield *Q*.

20 The proportions and details of construction may be considerably varied without departing from the present invention, as will be apparent.

The present invention enables the former style of thermostatic valve with a bow thermostat to be readily reconstructed to use the more desirable diaphragm thermostat. To do this the cover plate is removed, the bow thermostat and the stem which engages it and communicates its movement to the valve stem, are taken out, the stem *K K'* is put in place in lieu of the stem removed, and the lever *P*, thermostat *M*, and abutment *N*, are inserted in lieu of the bow thermostat.

With the construction shown the abutment *N* is shown as formed integrally with the front plate or cover *B*, and by this construction this cover *B* is substituted for the cover heretofore used, the parts being assembled by engaging the forked end of the lever *P* with the stem part *K'*, and afterward swinging the cover down into place against the casing. The adjusting of the screw *e* is made after the parts are thus assembled, and finally the cap *f* is screwed on.

I claim as my invention:—

1. In a steam inlet valve of the type described a narrow and substantially flat casing with a steam valve at one end and a valve stem traversing the casing longitudinally and the casing including a separable wall, a diaphragm thermostat carried by said separable wall and arranged transversely in the casing, and a lever receiving the expansive thrust of the thermostat and transmitting it to the valve stem.

2. The structure of claim 1 including a valve stem formed in two sections with ad-

justing means accessible outside the casing for varying their longitudinal relation.

3. In a steam inlet valve of the type described a narrow and substantially flat casing with a steam valve at one end and a valve stem traversing the casing longitudinally and formed in two sections with adjusting means for varying their longitudinal relation, a diaphragm thermostat and a lever receiving the expansive thrust of the thermostat, said lever having a forked end and one section of the valve stem having a collar with a projection entering the forked end of the lever so as to transmit the movement of the thermostat to the valve stem and prevent turning of the stem during adjustment.

4. The structure of claim 2 with the addition of a cap for inclosing the protruding end of the valve stem and adjusting means.

5. The structure of claim 1 with the addition of a deflecting shield to receive condensation and prevent its falling on the thermostat.

6. In a steam inlet valve of the type including a narrow and substantially flat casing with a steam valve at one end and a valve stem traversing the casing longitudinally, and a chamber through which the valve stem extends, the combination therewith of a thermostat operatively connected with said valve, an injector, a suction opening connecting the chamber and the injector, and a removable shield mounted in the chamber under said opening and above the valve stem and consisting of a plate adapted to intercept condensation falling from said opening and divert it to the opposite side walls of the casing.

7. The structure of claim 6, with the deflecting plate provided with dependent ears engaging the side walls of the chamber to hold the plate in position.

8. The structure of claim 1, with the casing inclosing the thermostat including a cover on one side and an abutment for the thermostat mounted on said cover whereby the thermostat and cover are removable together.

9. The structure of claim 8, the cover carrying also the pivotal connection for the lever so that removal of the cover carries with it the thermostat and lever.

In witness whereof, I have hereunto signed my name.

EDWARD E. GOLD.

Witness:

HARRY C. POILLON.
